The ornamental design for a shoe, as shown and described.

DESCRIPTION

FIG. 1 is a front bottom perspective view of a shoe showing my new design;

FIG. 2 is a bottom view thereof;

FIG. 3 is a rear bottom perspective view thereof;

FIG. 4 is a rear perspective view thereof;

FIG. 5 is a side view thereof;

FIG. 6 is a rear view thereof;

FIG. 7 is an opposite side rear perspective view thereof; and, FIG. 8 is an opposite side view thereof.

The outer layer of the sole element over the small spherical elements has a translucent or transparent appearance. Oblique line shading has been omitted over this area for clarity purposes. The curved oblique shade lines shown elsewhere on the claim represent transparent or translucent material. The broken lines immediately adjacent to the shaded areas define the bounds of the claimed design and form no part thereof. The broken lines depicting the remainder of the shoe show features that form no part of the claimed design.
